FIG 10

UNITED STATES PATENT OFFICE

2,365,036

FIREARM

Charles A. Young, Springfield, Ohio

Application January 26, 1939, Serial No. 252,919

15 Claims. (Cl. 42—20)

This invention pertains to repeating firearms of the magazine type and more particularly to alternate optionally selective fire control mechanisms therefor, and means for quickly converting the arm from safety controlled to straight fire operation and vice versa. In guns of this type a forearm is slidably mounted upon the magazine which has an action bar and a stop is provided for this action bar which retains the forearm and action bar against rearward movement when the gun is ready for firing. It has been usual to provide some sort of a lock for the sear which controls the hammer which is manually operated and which must be operated to release the sear before the gun can be fired.

In the present disclosure there is shown and described an optional fire control mechanism comprising an automatic sear lock controlled by the movement of the action bar, which forms the subject matter of my Patent No. 2,200,868, issued May 14, 1940, upon a copending application Serial No. 227,781, filed August 31, 1938, of which the present application is a continuation in part, with which is combined alternative fire control mechanism from which the sear lock feature is eliminated, so that the gun may be employed in straight fire operation.

By safety control operation is meant the condition wherein the impact member or hammer is normally locked against accidental discharge and must be unlocked each time the gun is fired, preparatory to release of the impact member or hammer, which in the illustrated construction is effected by a final retractive movement of the action bar. By straight fire operation is meant the condition of operation wherein the impact member or hammer lock is disabled and the hammer is free for release and is conditioned for repetitive firing operations without the necessity of unlocking the hammer preparatory to each firing operation.

In the present instance provision is made for converting the firearm from one such condition of operation to the other, while permitting repetitive firing operations under both conditions of use.

The present construction is an amplification of the aforementioned patented structure whereby the gun is optionally operable either with or without the forearm and action bar controlled safety sear lock feature. In this respect it differs from other known prior art structures wherein when the safety feature is disabled, the gun is rendered unusable.

The object of the invention is to improve the

construction as well as the means and mode of operation of firearm safety features wherein the gun is adapted to a wider range of used and for optional operation with or without such safety fire control devices.

A further object of the invention is to provide alternate optionally selective fire control means, and a manual means adjusting device by which the gun may be easily and quickly converted from straight fire operation to safety controlled operation, and vice versa.

A further object of the invention is to amplify the disclosure of my Patent No. 2,200,858 by adding thereto means for optionally rendering the forearm and action bar controlled safety features ineffective and enable the alternate normal operation of the gun.

A further object of the invention is to provide alternate forms of control means for converting the safety fire control operation into a straight fire operation.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

In the accompanying drawings:

Fig. 1 is a view partly in side elevation and partly in longitudinal section of so much of a gun as is necessary to illustrate the first form of the invention, the parts being shown in firing position with the impact member or hammer cocked.

Fig. 2 is a top plan view of some of the parts shown in Fig. 1 after the gun has been fired.

Fig. 3 is an enlarged side elevation of the parts shown in Fig. 2 and also an enlargement of some of the parts shown in Fig. 1 with the exception that the action parts are shown after the gun has been fired instead of before firing as shown in Fig. 1.

Fig. 4 is a fragmentary vertical section on a slightly enlarged scale on the line 4—4 of Fig. 3 showing some of the parts in one working position.

Fig. 5 is a view similar to Fig. 4 but with the parts in a different working position.

Fig. 6 is a fragmentary elevation of a portion of the action from the opposite side as seen in Fig. 1 and on a slightly enlarged scale as compared to that view.

Fig. 7 is a fragmentary sectional view on the

line 1—1 of Fig. 4 on an enlarged scale with the parts in one working position.

Fig. 8 is a view similar to Fig. 7 with the parts in a different working position.

Fig. 9 is a perspective view of a detail on the same scale as is employed in Fig. 3.

Fig. 10 is a view partly in side elevation and partly in longitudinal section of the second form of my invention, the parts being shown in firing position with the impact member or hammer cocked.

Fig. 11 is an enlarged top plan view of some of the parts shown in Fig. 10.

Fig. 12 is an enlarged side elevation of some of the parts shown in Fig. 10.

Fig. 13 is an elevation of a detail hereinafter described.

Referring first to the form of the invention shown in Figs. 1 to 9, inclusive, of the drawings, 1 represents a portion of the barrel of the gun, 2 a portion of the stock and 3 the housing which encloses and supports the action. The usual breech block is indicated at 4 and firing pin at 5. A portion of the magazine is indicated at 6 and a portion of the forearm at 7, the forearm being slidably mounted upon the magazine and having the usual action bar 8 which when the forearm is manipulated serves to retract the breech bolt, to cock the impact member shown in the present case as a pivoted hammer 9, eject the exploded shell and place a new shell upon the shell carrier 10.

The stop for the action bar is indicated at 11, this stop being in the nature of an elongated bar which is pivoted at 12. The main spring for the hammer is indicated at 13, this spring being a coil spring which encircles a rod 14, which is slidably mounted at its rear end in a bridge portion 15 of the action support 16, and has its forward end pivotally connected to the hammer by a head 17 which is pivoted to the hammer by the pin 18. This head 17 has connected therewith a spring wire or rod 19, the rear end of which is formed with a bent portion 19' which extends into a groove 20 of a plate 21 which is fastened to the action bar stop 11 as a result of which when the hammer is moved to cocking position the action bar stop will be tilted to a position to bring the forward end thereof in the path of the action bar but when the gun is fired the stop will be tilted to a position out of the path of the action bar.

The pivot pin 12 for the stop 11 extends into a slotted opening 22 in a portion of the frame 16 so that the stop will be permitted a limited rearward movement against the tension of a coil spring 23, one end of which is connected to the stop and the other end to a suitable portion of the frame. The stop 11 has on its rear end a foot 24 which contacts with an abutment 25 to limit rearward movement.

The sear which engages the notch 9' in the hammer is indicated at 26 and in the present case is shown as an integral part of the trigger 27 which is pivoted at 28. A small coil spring 26' serves to move the sear to a position to engage the hammer when the hammer is cocked. The forward end of the sear has a small projection 26" which cooperates with a lock for the sear.

In this form of the invention the lock is shown as a rotatable pin 29 which is rotatably mounted in a portion of the finger guard 30 and is held against endwise movement in one direction in any suitable way such as by the side of the housing 3. The pin has a notch 31 which is brought

into or out of the path of the projection 26" by rotation of the pin. To rotate the pin the pin has a projecting finger 32 which extends into a yoke 33 which projects from the stop 11.

In this form of the invention in order to convert the gun from safety fire control to straight fire operation the pin is slidably mounted so that it can be forcibly moved from left to right. When it is so moved it will be snapped over the bent portion 34 of a spring 35 (best shown in Fig. 6) so that the bent portion will engage in a recess 36 to yieldably hold the locking pin in disabled position. It may be stated that this bent portion 34 also serves by engagement with the end of the pin to hold the pin in its operative locking position just described. When the pin is moved to the right a low portion 37 is brought beneath the sear so that the locking pin will have no effect upon the sear and the gun may be used as a straight action gun. It may be stated that when the locking pin is moved to disabled position the projection 32 will of course be moved out of the forked portion 33 of the action stop and into a recess 38 in the frame. In the operation of this form of the invention when the locking pin is in its locking position, and the gun is fired the spring 19 sliding in the groove 20 swings the stop 11 out of the path of the action bar so that the forearm and its action bar may be moved rearwardly to perform their proper functions, one of which is to cock the hammer. The action bar by reason of its close proximity to the enlargement 11' on the forward end of the stop holds the stop against return movement. This results in the spring 19 being moved to the other end of the groove and bearing thereon so as to tilt the stop 11 as soon as the action bar has been moved out of the way with the enlargement 11' thereof to the position shown in Fig. 1. In the meantime the spring 23 has moved the stop 11 forwardly so as to rock the lock 29 to the position shown in Figs. 4 and 7 to thereby lock the sear. If it is desired to fire the gun it is necessary to move the forearm slightly to the rear which causes the action bar 8 by contacting the enlargement 11' of the stop 11 to move the stop rearwardly against the abutment 25 which rocks the locking pin 29 to the position shown in Fig. 6 to thereby unlock the sear. The shooter must hold the forearm and action bar in this position until the gun is fired. In the event that it is desired to delay the firing of the gun for any reason the shooter by merely releasing the forearm permits the arm, action bar and action bar stop to be moved forwardly under the influence of the spring 23 to again rock the locking pin to the position shown in Figs. 4 and 7 and lock the sear.

When the locking pin is moved to its alternate position by which the gun is converted from safety fire control to straight fire operation, the sear will be entirely unlocked thereby, the only lock for the hammer being the detent connected with the trigger, so that the gun may be used as a straight action gun.

Referring now to Figs. 10 to 13, 41 represents a portion of the barrel of the gun, 42 a portion of the stock and 43 the housing which encloses and supports the action. The breech block is indicated at 44 and firing pin at 45. A portion of the magazine is indicated at 46 and a portion of the forearm at 47, the forearm being slidably mounted upon the magazine and having attached thereto the usual action bar 48 which when the forearm is manipulated serves to retract the breech bolt

to cock the impact member shown in the present case as a pivoted hammer 49 and perform its other usual functions which are not a part of this invention.

The stop for the action bar is indicated at 51, this stop being in the nature of an elongated bar which has an extension 51' to form a release which is no part of the present invention. This stop 51 is pivotally mounted upon a pin 61 which is the pin upon which the sear is pivoted. The main spring for the hammer is indicated at 53, this spring being a coil spring, the forward portion of which is located in a slidably mounted hollow plunger 54 and the rear portion of which encircles the fixed pin 55. The forward end of this plunger has a conical depression to receive the conical end of a link 56, which link is pivotally connected to the hammer by a pin 57. The forward end of the plunger 54 has connected therewith an angularly shaped member 58, the angular portion of which is located in a slot 51'' in the action bar stop 51 as a result of which when the hammer is moved to cocking position the action bar stop will be tilted upwardly to a position to bring the forward end thereof in the path of the action bar but when the gun is fired the stop will be tilted downwardly to a position out of the path of the action bar. The action bar stop is moved rearwardly by the action bar against the tension of a spring to be described which spring action will project it forwardly when the gun is fired.

The member 58 is shifted to and fro intermediate the upper and lower arms of the bifurcated member 51 in unison with the movement of the spring plunger 54, incident to the cocking and release of the hammer.

In such movement, the spring plunger 58' is caused to bear on the lower arm of the member 51 alternately at opposite sides of its pivot 61. This causes the member 51 to be tilted with its forward end elevated into the path of the action bar when the hammer is cocked, and to be automatically depressed upon release of the hammer.

The sear which engages the notch 49' is indicated at 59 and in the present case is shown as an integral part of the trigger 60 which is pivoted at 61. A small coil spring 62 serves to move the sear to a position to engage the hammer when the hammer is cocked.

In this form of the invention the lock for the trigger and sear is shown as a bell crank pivoted at 63, the long arm 64 of which projects to engage or disengage the trigger and the short arm 65 of which projects in proximity to a pin 66. The locking portion 64 of the bell crank lever is urged to locking position by a plunger 67 and spring 68 but is thrown out of locking position by the rear end of the stop 51 when moved rearwardly by the action bar. In the present case the action bar has connected therewith a member 69 having a tail portion 70 which extends to the forward end of the stop 51 so that when the stop is in the path of the member 69 it will be moved rearwardly to cause the stop to put a pressure upon the arm 64 of the bell crank lever and release the trigger. When the gun is fired, however, the plunger 54 and the angular member 58 connected therewith will move forward and downward pressure will be exerted upon the stop 51 by the spring plunger 58' to bring the forward end thereof downwardly out of the path of the member 69 of the action bar. At the same time the locking part 64 of the bell

crank lever will be moved forward by the plunger 67 as well as the action bar stop so as to be in a position to again engage the trigger when the trigger is released.

5 This part of the construction is the same in principle as that shown in Figs. 1 to 9, inclusive, the difference being the form of means for disabling or throwing the lock 64 out of commission which lock will now be described. The 10 pin 66 has thereon a lip 71 and this pin is rotatably mounted so that the lip 71 can be projected beneath the rear end of the short arm 65 of the bell crank lever so as to tilt the bell crank lever to the position shown in Fig. 10 15 in which position the gun may be used as a straight fire gun.

In this case the lip 71 is turned sufficiently beneath the short arm 65 to engage the notch 65' in the arm to hold the pin in position during firing of the gun. The pin 66 is provided with a head 66' having a slot 66'' to receive a suitable tool, which head is located on the outside of the gun for ready manipulation.

Having thus described my invention, I claim:

25 1. In a gun of the character described, an impact member, a trigger-operated sear to hold said member cocked, a lock for said sear, an actuating device, and means operated by a limited rearward movement of said device to operate said lock to release said sear, said sear lock being mounted for alternative movement into operative position, wherein it is capable of further movement into and out of locking relation with the sear under influence of the actuating device, and into an inoperative position beyond the field of influence of the actuating device, wherein it is incapable of locking engagement with the sear.

30 2. In a gun of the character described, an impact member, locking means for temporarily preventing release of the impact member, a slidably mounted action bar, means for mounting the locking means for movement into and out of alternate positions in one of which it is adjustable into and out of relation to prevent release of the impact member, means operated by a limited 35 rearward movement of the action bar to operate the locking means to release the impact member when the locking means is in the said one position, the locking means being ineffective when in the other of said alternative positions to prevent release of the impact member during any portion 40 of the cycle of operation of the gun.

45 3. In a gun of the character described, an impact member, a locking means for temporarily preventing release of the impact member, a slidably mounted fore arm, a reciprocatory action bar connected therewith, means operated by a limited rearward movement of said fore arm and action bar to operate the locking means to permit release of the impact member, a mounting in which the locking means is bodily movable into and out of alternate positions, in one of which it is adjustable under control of the fore arm and action bar into and out of relation to prevent 50 release of the impact member, and in the other of which it is beyond control of the action bar and ineffective to prevent release of the impact member during any cycle of operation of the gun.

55 4. In a gun of the character described, an impact member, locking means for temporarily preventing release of the impact member, a slidably mounted action bar, a yieldable stop for said action bar having limited movement and operatively associated with said locking means, means 60 operated by the impact member to move the stop 65

70

into and out of the path of the action bar, the stop being in the path of the action bar when the impact member is cocked, and means operated by a limited rearward movement of the bar to move said stop and cause the same to operate said locking means to permit release of said impact member, a mounting in which the locking means is mounted for movement into alternate effective and ineffective positions in the first of which it is capable of further alternating adjustment under control of the action bar into and out of relation to prevent release of the impact member while in the latter of which it is incapable of preventing release of the impact member during any portion of the cycle of operation of the gun.

5. In a gun of the character described, an impact member, a trigger-operated sear to hold said member cocked, a lock for said sear, a slidably mounted actuating device, a stop member for said device having a limited movement, means to connect said stop member with said lock, means operated by the impact member to move said stop member into the path of said actuating device when said impact member is cocked and to move it out of the path of said actuating device when the gun is fired, a spring for said stop member normally tending to move it to a position to move said lock to locking position, said actuating device by a limited rearward movement thereof adapted to contact said stop member and move it a limited distance against the tension of said spring to cause it to move the lock to unlocking position, said sear lock being mounted for alternating movement into and out of operative and inoperative positions, in the first of which it is effective to lock and unlock the sear under control of the actuating device, and in the latter of which it is ineffective to lock the sear during any portion of the cycle of operation of the gun.

6. In a gun of the character described, an impact member, a trigger-operated sear to hold said member cocked, a lock for said sear, a slidably mounted action bar, a yieldable stop for said action bar having a limited movement and operatively associated with said sear lock, means to throw the stop into and out of the path of said action bar, the stop being in the path of said action bar when the impact member is cocked, means operated by a limited movement of said stop when operated by a limited rearward movement of said action bar to move said stop to cause the same to rock said sear lock to unlock said sear, and means for mounting the lock for movement into and out of alternate positions in one of which it is adjustable by said limited movement of said stop.

7. In a gun of the character described, an impact member, a trigger-operated sear to hold said member cocked, a lock for said sear consisting of a rotatable pin having a notch in one portion thereof and also having a low portion, an actuating device, and means operated by a limited rearward movement of said device to rotate said pin to bring the notch in the path of the sear to temporarily release said sear, said pin being slidably mounted to bring the low portion thereof in the path of said sear to entirely free said pin from said sear.

8. In a gun of the character described, an impact member, a trigger-operated sear to hold said member cocked, a lock for said sear consisting of a rotatable pin having a notch in one portion thereof and a low portion in another portion thereof, a slidably mounted action bar, and means

operated by a limited rearward movement of said bar to rotate said pin to bring the notch in the path of said sear to unlock said sear, said pin being slidably mounted so that the low portion thereof can be brought into the path of said sear to entirely free said pin from said sear.

9. In a gun, a fire control mechanism optionally convertible from safety control condition to free straight fire condition, including an impact member, a slidably mounted action bar, locking means normally preventing release of the impact member and operable by a limited rearward movement of said action bar to release said impact member during a period of safety control operation, a mount for said locking means wherein the locking means is manually adjustable to an idle position during a period of straight, free fire operation wherein repetitious unrestricted cycles of the gun operation is permitted.

10. In a gun, fire control mechanism alternately subject to safety control operation and free straight fire operation, including an impact member, a slidably mounted action bar, a movable stop for said bar subject to limited rearward movement by a rearward pull upon said bar, locking means normally preventing release of the impact member during a period of safety control operation and operable through medium of said stop upon the aforesaid limited rearward movement thereof under influence of the action bar to permit release of the impact member, a mount for said locking means wherein the locking means is manually adjustable to an idle position beyond control of the stop and action bar, during a period of straight free fire operation of the gun.

11. In a gun, a fire control mechanism optionally convertible from a condition of safety control operation to a condition of free straight fire operation, including an impact member, locking means normally preventing release of the impact member during a period of safety control operation, a slidably mounted actuating device therefor by a limited rearward movement of which the locking means is adjusted to permit release of the impact member, a mount for the locking means wherein it is adjustable to a position so as to be ineffective to control release of the impact member during a period of straight free fire operation of the gun.

12. In a gun, a fire control mechanism optionally convertible from safety control condition to straight free firing condition and vice versa, including an impact member, locking means normally preventing release of the impact member during a period of safety control operation, a slidably mounted actuating device, a movable stop capable of limited rearward movement into and out of the path of the actuating device and engageable thereby when the impact member is cocked, said stop being operatively associated with said locking means, and operated by the movement of the actuating device to adjust said locking means to permit release of the impact member, a mount for said locking means in which the locking means is movable to an idle position wherein it is ineffective to control operation of the impact member during a period of straight free fire operation of the gun.

13. A fire arm wherein an impact firing member is retracted by a reciprocating action bar and restrained in its retracted position by engagement therewith of a trigger operated sear, characterized by a fire control mechanism optionally convertible alternately for safety control operation and free straight fire operation, including a

locking member arranged to temporarily lock said sear, means for mounting said locking member for both rotary and reciprocatory adjustment, means responsive to reciprocatory motion of the action bar to oscillate said locking member into and out of sear locking relation, said locking member being manually reciprocable into and out of operative relation with the sear.

14. An optionally operable straight fire and safety controlled fire arm wherein an impact firing member is retracted by a reciprocatory action bar, characterized by a locking member, a mounting in which the locking member is capable of both oscillatory and reciprocatory motion, said locking member being subject to oscillatory adjustment under control of the action bar during a period of safety control operation into and out of position to prevent release of the firing member while in one position of reciprocatory adjustment and inoperative to prevent release of the firing member and beyond influence of the

action bar while in another position of reciprocatory adjustment during a period of straight free fire operation.

15. In a gun of the character described, an impact member, a trigger operated sear to hold said member cocked, a lock for said sear in the form of a pivoted bell crank lever, a slidably mounted action bar, a yieldable stop for said action bar having a limited movement and operatively associated with one arm of said bell crank lever, means to throw the stop into and out of the path of said action bar, the stop being in the path of said action bar when the impact member is cocked, means operated by a limited movement of said stop when operated by a limited rearward movement of said action bar to move said stop to cause the same to rock said sear lock to unlock said sear, and a movable member operable upon the other arm of said sear lock to hold the same out of sear locking position.

CHARLES A. YOUNG.
